Patented July 21, 1914.

UNITED STATES PATENT OFFICE.

JOSIAH PERCIVAL STEVENS, OF ATLANTA, GEORGIA.

SAFETY-RAZOR.

1,104,570.

Specification of Letters Patent. Patented July 21, 1914.

Application filed February 21, 1914. Serial No. 820,242.

To all whom it may concern:

Be it known that I, JOSIAH PERCIVAL STEVENS, a citizen of the United States, residing at Atlanta, in the county of Fulton and 5 State of Georgia, have invented certain new and useful Improvements in Safety-Razors; and I do hereby declare the following to be a full, clear, and exact description of the invention, such as will enable others skilled 10 in the art to which it appertains to make and use the same.

My present invention relates to improvements in safety razors, and it is intended to provide a cheap and simple form of safety 15 razor in which the razor blade is firmly held in place when desired, and in which the parts are readily assembled and disassembled for the purposes of cleaning, renewal, or the like.

20 It is well known that with the safety razors now generally in use, there is more or less annoyance in taking the razor apart and cleaning up the same, and restoring the parts to the assembled position each time the 25 razor is used; and the object of my present invention is to simplify and reduce the number of these parts, and to facilitate the operation of assembling and disassembling the same, as will be hereinafter described and 30 claimed.

Reference is had to the accompanying drawings, in which:

Figure 1 is a plan view of the safety razor with the parts assembled and ready 35 for use; Fig. 2 shows an inverted plan of the device, with the parts as shown in Fig. 1; Fig. 3 shows the razor blade in position, and the resilient clamp swung away therefrom; Fig. 4 shows the parts in the position 40 of Fig. 3, except that the razor blade has been removed from its support; and Fig. 5 shows a section through the support, razor blade, and resilient clamp, along the line 5-5 of Fig. 1, and looking in the direction 45 of the arrows.

A represents the rigid supporting piece, or support, on which the razor blade is mounted when in use. This support is provided with the usual guard teeth a , and is 50 provided with any suitable means for holding the razor blade in place, such, for instance, as the lugs a' . On the opposite side, near its outer end, the support is provided with the stud a^2 to engage the fork in the 55 resilient clamp, as will be hereinafter described.

The outer end of the support is preferably curved slightly, as at a^3 , and this support is provided with a flattened portion a^4 and an inclined face a^5 near the handle B. 60 This handle is pivoted to the blade, as at b . The stud C is secured to the flattened portion a^4 of the razor support, and has its shank e projecting down through the slot e in the resilient clamp E, the rear end of 65 which clamp is provided with a thumb lug e' . The front end of this clamp is bent over, as at e^2 , to engage the front end of the razor support, and this bent-over portion e^2 is provided with beveled jaws e^3 terminating in 70 the holding notch e^4 adapted to engage the stud a^2 on the razor support when the clamp is in the locked position shown in Figs. 1 and 2.

To assemble the parts, swing the clamp 75 E clear of the support, as shown in Fig. 4, apply the razor blade, as shown in Fig. 3, then swing the clamp until the jaws e^3 are in line with the axis of the razor blade, at the same time moving the clamp forward 80 longitudinally relative to the stud C, so as to permit it to pass freely over the end a^3 of the support A, and then slide the clamp backward until the stud a^2 , guided by the beveled jaws e^3 , enters the slot e^4 . These 85 jaws will bind the clamp in place against longitudinal displacement, and the razor may be used as in the ordinary way. To dis-assemble the parts, press the thumb lug e' outward, causing the stud a^2 to disengage 90 from the notch e^4 , and clear the jaws e^3 , then swing the clamp to the position shown in Fig. 3 and remove the razor blade. It will thus be noted that the clamp E is locked and 95 unlocked by a sliding motion, and is held permanently attached to the razor support, but at the same time readily accessible for the purpose of cleaning; thus the only removable part is the razor blade.

While I have shown the razor blade slot- 100 ed, as at d , and attached to the support by lugs a' in the usual way, it will be obvious that the razor blade may be connected to the support in any convenient way, and clamped in place by the improved resilient clamp 105 herein described. It will also be obvious that various other changes might be made in the construction, combination and arrangement of parts which could be used without departing from the spirit of my in- 110 vention.

Having thus described my invention, what

I claim and desire to secure by Letters Patent of the United States is:—

1. In a safety razor, the combination with a support for the razor blade provided with a rearwardly-projecting arm, and a handle attached to said arm, a pin attached to said rearwardly-projecting arm, means for detachably connecting said blade to the support, and a resilient clamp engaging the outer end of said arm and having a slot engaging said pin, said clamp being adapted to swing laterally about said pin and to slide longitudinally thereon, thus to release the razor blade when desired and to lock the said razor blade on said holder, substantially as described.
2. In a safety razor, the combination with a razor support provided with means for attaching the razor blade to one side thereof, a headed stud connected to said support on the same side with said razor-holding means, a lug provided on the opposite side near the outer end thereof, and a resilient clamp slotted longitudinally to engage said stud and bent over at its outer end, and pro-

vided with jaws to engage said lug, the said resilient clamp being adapted to lock said razor blade in place and to release same when desired, substantially as described.

3. In a safety razor, the combination with a razor support provided with means for attaching the razor blade to one side thereof, a headed stud connected to said support on the same side with said razor-holding means, a lug provided on the opposite side near the outer edge thereof, a resilient clamp slotted longitudinally to engage said stud and bent over at its outer end, and provided with jaws to engage said lug, and a thumb lug provided on the inner end of said clamp in rear of said slot, the said resilient clamp being adapted to lock said razor blade in place and to release same when desired, substantially as described.

In testimony whereof, I affix my signature, in presence of two witnesses.

JOSIAH PERCIVAL STEVENS.

Witnesses:

ERNEST WILKINSON,
R. M. PARKER.
